INVENTOR,

J. A. Kenworthy

J. M. Wright,

ATTORNEY.

UNITED STATES PATENT OFFICE.

JAMES A. KENWORTHY, OF OAKLAND, CALIFORNIA.

GAS-GENERATOR.

No. 913,738.

Specification of Letters Patent.

Patented March 2, 1909.

Application filed April 3, 1908. Serial No. 124,985.

To all whom it may concern:

Be it known that, JAMES A. KENWORTHY, a citizen of the United States, residing at Oakland, in the county of Alameda and State of California, have invented new and useful Improvements in Gas-Generators, of which the following is a specification.

This invention relates to an apparatus for carbureting air, so as to produce a combustible gas from gasolene or other volatile oil, without the use of heat to vaporize the oil.

The objects of the invention are to provide a device of this character which will be simple and economical in construction, compact in form, and safe in operation, whereby it can be used in households for the purpose of providing a combustible gas either for fuel or for lighting, at comparatively small expense, and with convenience and safety.

20 In the accompanying drawing, Figure 1 is a front view partly in vertical section, showing my improved apparatus in use with a stove and a gas burner; Fig. 2 is a horizontal section on the line 2—2 of Fig. 1.

25 Referring to the drawing, 1 indicates an air pump, which is here shown as of the kind operated by hand, although it may be a pump operated by water, electricity, or any suitable source of power. To said pump 30 is connected a receiver 2 adapted to contain air at a high pressure, and having a pressure gage 3. From said receiver a pipe 4 leads through a reducing valve 5, said pipe, beyond said reducing valve, being supplied 35 with a pressure gage 6. The pipe 4 leads to the top of a pipe 7 extending downwardly through the head 8 of a cylindrical casing 9.

40 Through the head 8 of said casing, at one side of the center, is a filler tube 10, extending to a point near the bottom of the casing, for supplying said casing with oil. Secured in the center of said head 8 around the pipe 7 is a cylindrical gas outlet conduit 11 having a lateral outlet connected with a pipe 13 45 leading to the bottom of a gas holder 14, and discharging into water at the bottom of said gas holder through a perforated pipe 15. From the top of said gas holder a pipe 16 leads to any place where it is desired to use 50 the gas, as a stove 18 and burner 19.

The bottom of the pipe 7 is connected to the center of a cruciform conduit 20, to the four terminals of which are connected four elbows 21, to the ends of which are screwed 55 nozzles 22 directed upwards. Each nozzle discharges upwards into the open lower end

of a vaporized cylinder 23. At about the middle of each cylinder is secured a transverse partition 24 having a central aperture 25 across which is interposed a screen 26. 60 When the compressed air emerges from a nozzle into any one of said cylinders it passes through the oil therein, but, owing to the resistance offered by the oil to the passage of the air therethrough, a certain 65 quantity of the oil is carried through the screen with the air into the upper chamber 27 above said partition, the air which is not able to immediately force its way through the screen into the upper chamber collecting 70 to a certain extent below said partition and its screen. The air passing through the screen now passes upwards through the oil in the upper chamber and emerges from the top of the vaporizing cylinder by a narrow 75 pipe 28. But owing to the fact that the air emerges through this pipe under considerable pressure the tendency is for the air to carry with it considerable oil in the form of spray or mist. To separate the fine particles 80 of oil from the air, I provide above each of these narrow pipes a screen 29, through which the air is compelled to flow, the oil spray collecting against said screen, and dripping back into the receptacle. For a 85 similar reason, in order to separate from the air all oil which has not been thoroughly gasified, I provide a screen 30 at the bottom of the gas outlet, so that air passing through said screen 30 is thoroughly gasified and no 90 oil can pass therethrough which will afterwards tend to collect in a liquid form in the pipes.

It will be seen that by the above arrangement there is provided a carbureter, which 95 is compact in form, simple in construction and safe in operation.

I regard as one of the most important features of the invention, the screens for separating from the air such portion of the 100 oil as is in the form of fine particles of liquid, which particles are readily carried by the air but would tend to collect in the pipes. By means of these screens, such particles are arrested, and only purely gaseous 105 products are permitted to pass into the pipe.

I claim:—

1. A carbureter comprising a casing adapted to contain volatile oil, a plurality of receptacles therein open at the bottom to 110 the entrance of the oil, a pipe extending to the bottom of the casing, conduits leading

from the bottom of said pipe, one for each receptacle, and discharging upwardly into the open bottom of said receptacle, contracted outlets at the tops of the receptacles, 5 screens arranged horizontally above said outlets, against which the air emerging from the receptacles impinges, a discharge conduit for the gas, and a screen covering the bottom of the discharge conduit, substantially as described.

2. A carbureter comprising a casing adapted to contain volatile oil, a plurality of receptacles therein open at the bottom to the entrance of the oil, a pipe extending to the 15 bottom of the casing, conduits leading from the bottom of said pipe, one for each receptacle, and discharging upwardly into the open bottom of said receptacle, a horizontal

partition arranged at the middle of each receptacle and having a central opening, a screen across said opening, contracted outlets at the top of the receptacles, screens arranged horizontally above said outlets, against which the air emerging from the receptacles impinges, a discharge conduit for 25 the gas, and a screen covering the bottom of the discharge conduit, substantially as described.

In testimony whereof I have hereunto set my hand in the presence of two subscribing 30 witnesses.

JAMES A. KENWORTHY,
